SHEET HOLDER

Bruce K. Slonberger, Dayton, Ohio

Application March 12, 1949, Serial No. 81,069

19 Claims. (Cl. 281—44)

1

This invention relates to a sheet holder and is designed more particularly for use with sales slips or the like, but may be used with sheets of various kinds.

One object of the invention is to provide a sheet holder in which the closure is movable lengthwise of the body of the holder to position the same in supporting relation to a withdrawn sheet and is also bodily movable to a position providing free access to the interior of the holder.

A further object of the invention is to provide such a sheet holder in which the closure has both sliding movement and pivotal movement with relation to the body of the holder.

A further object of the invention is to provide such a sheet holder in which the retained portion of a used sheet may be moved from the upper side of the sheet supporting member to the lower side thereof without detaching the same from the supporting member.

A further object of the invention is to provide such a sheet holder in which the sheet supporting member is pivotally supported at one end in the holder and is provided at its free end with sheet attaching means which permit the attached sheets to be moved from one side thereof to the other side thereof.

A further object of the invention is to provide such a sheet holder in which a sheet supporting member may be connected with the closure for movement therewith when the closure is moved about its pivotal axis.

A further object of the invention is to provide such a sheet holder in which that end of the sheet supporting member with which the sheets are connected is pivotally supported for movement to a position to permit access to the holder below the supporting member.

A further object of the invention is to provide such a sheet holder in which the closure is movable rearwardly with relation to the sheet supporting member to provide an extended hand rest on which the hand may rest upon making an entry on the uppermost sheet.

Other objects of the invention may appear as the sheet holder is described in detail.

In the accompanying drawings Fig. 1 is a top plan view of a sheet holder embodying the invention, partly broken away, and showing the closure in an intermediate position; Fig. 2 is a side elevation of the holder as shown in Fig. 1 with one side wall thereof broken away; Fig. 3 is a transverse section taken on the line 3—3 of Fig. 2; Fig. 4 is a side elevation of the holder showing the closure partly broken away and extending

2

outwardly from the body of the holder; Fig. 5 is a top plan view, partly broken away, of a modified form of the sheet holder; Fig. 6 is a side elevation of the sheet holder of Fig. 5; Fig. 7 is a side elevation of the sheet holder of Fig. 5 showing the closure and sheet supporting member in outwardly extending positions, one side wall of the holder being partly broken away; Fig. 8 is a side elevation of another form of sheet holder, with one side wall of the holder partly broken away and showing the closure and sheet supporting member in outwardly extending positions; Fig. 9 is a side elevation of another form of sheet holder with one side wall of the holder partly broken away, and with the closure and sheet supporting member in outwardly extending positions; and Fig. 10 is a side elevation of another form of holder showing the upper member or closure in an inclined position with relation to the lower member of the holder.

In these drawings I have illustrated certain embodiments of the invention but it is to be understood that the invention may be embodied in sheet holders of various kinds and that the sheet holder as a whole, as well as the various parts thereof, may take various forms without departing from the spirit of the invention.

In each illustrated form the sheet holder comprises a lower member, a sheet supporting member adapted to support a pile of superposed sheets on or in the lower member and so supported that at least one end portion thereof may be moved outwardly from the lower member, said supporting member being provided at its forward end with means for retaining said pile of sheets thereon. An upper member, or closure, is connected with the lower member for movement lengthwise of the latter to expose the uppermost sheet of the pile of sheets and for pivotal movement with relation to the lower member to a position which will permit the movable portion of said sheet holder to move, or to be moved, outwardly from the lower member. In use the sheet holder is usually supported in a substantially horizontal position, either by the hand of the operator or on a table, and when so supported the outward movement of the sheet supporting member is an upward movement.

In that embodiment illustrated in Figs. 1 to 4 the lower member of the sheet holder comprises a shallow receptacle having a bottom wall 10, side walls 11, a rear wall 12 and a front wall 13. The front wall is preferably provided with a rearwardly extending upper portion 14 and in the present instance it is shown as substantially

semi-circular in form and is bowed forwardly beyond the ends of the side walls 11. Elongate members 15 are pivotally connected with the forward portion of the receptacle and normally extend rearwardly along the respective lateral edges thereof. An upper member or closure 16 is mounted on said elongate members for movement toward and from the pivotal axis of the latter. In the arrangement shown the front end wall 13 of the receptacle is provided at its upper edge with bearings 17 and the elongate members 15 are shown as round rods the end portions of which are bent inwardly and rotatably supported in the respective bearings 17. The closure 16 is provided at its lateral edges with downwardly and inwardly extending parts 19 forming guideways to receive the elongate members 15 and slidably support the closure thereon.

A sheet supporting member 20 is supported in the receptacle and is adapted to receive and support a pile of superposed sheets, 21. In the present instance the sheet supporting member comprises a sheet of metal pivotally connected at its rear end with the receptacle and curved about a transverse axis so that the forward portion thereof is biased upwardly. For a purpose, which will hereinafter appear, the pivotal axis of the sheet supporting member preferably has limited vertical movement and as here shown screws, or studs, 22 extend into the rolled rear end portion 22a of the supporting member and are rotatably and slidably mounted in slots 23 in the side walls 11 adjacent the rear ends thereof.

The sheet supporting member is provided at its forward end with sheet attaching, or retaining, devices and these attaching devices are preferably of such a character that a sheet supported on the upper side of the sheet supporting member may be moved about the end of the supporting member to a position on the lower side thereof between the supporting member and the bottom wall 10 of the receptacle. In the preferred construction each attaching device comprises two semi-circular members 24 the adjacent ends of which, at one side of the device, are pivotally connected one with the other and the other ends thereof are arranged in alignment and are preferably overlapped, as shown at 25. Thus each attaching device is annular in form. Each annular device is connected with the forward end of the sheet supporting member 20 and is preferably movable about an axis parallel to the supporting member. In the present instance the supporting member is provided at its forward end with bearings 26 in which is mounted a rod 27 and the first mentioned end portions of the semi-circular members 24 are pivotally mounted on that rod and are held in contact one with the other by a spring 28 mounted about the rod 27 and confined between the adjacent semi-circular members of the two attaching devices. Thus it will be apparent that the two parts of each attaching device may be separated to permit one of said semi-circular members to be inserted through openings in the pile of sheets 21 and then closed to retain the sheets thereon. When the closure 16 is in its closed position the forward end of the supporting member and the attaching devices are wholly within the receptacle, the supporting member flexing to permit the same to move inwardly, and they are retained in this position by the closure. The sheets 21 are here shown as single sheets but ordinarily a sales sheet comprises at

least two connected but separable portions arranged one below the other with a transfer medium between adjacent portions, and the term "sheet" is herein used to include either a single sheet or a multiple sheet. When an entry is to be made on a sheet the closure is moved rearwardly on the elongate members 15 to expose the major portion of the uppermost sheet of the pile. The retraction of the closure permits the forward ends of the supporting member and the sheets to move upwardly so that the ends of the sheets are then supported above the level of the closure. The rear or unattached end of the uppermost sheet is then withdrawn from the pile and the closure moved forwardly beneath the withdrawn sheet to provide writing support therefor while the entry is being made.

When the entry has been completed the detachable portion or portions of the sheet are detached and the remaining or record portion of the sheet, through which the attaching devices extend, remains attached to the supporting member. The closure is then swung outwardly about its axis and the supporting member and the sheets thereon are moved outwardly about the rear pivotal axis of the supporting member so that the forward end portion of the supporting member and the attaching devices are spaced a substantial distance from the receptacle, somewhat greater than the distance shown in Fig. 4. The attached portion 21a of the used sheet is then moved, on the annular attaching devices, about the end of the supporting member to a position on the lower side of the supporting member and when the supporting member is returned to its normal position the used sheet lies between the supporting member and the bottom of the receptacle, that is, in the lower compartment of the receptacle, which is divided by the supporting member into an upper compartment for unused sheets and a lower compartment for used sheets, as shown at 21b. As the sheets are moved successively from the upper compartment to the lower compartment the number of sheets on the lower sides of the attaching devices increases with relation to the number of sheets on the upper sides thereof and this increased number of sheets on the lower sides of the attaching devices causes the latter to move about their pivotal connections with the supporting member so as to gradually lower the connected ends of the used sheets. Likewise as the number of sheets in the lower compartment increases with relation to the number of sheets in the upper compartment the rear end of the supporting member moves upwardly so as to increase the space between the supporting member and the bottom of the receptacle.

While it is preferable to swing the closure and the supporting member outwardly about their respective pivotal axes distances sufficient to enable the used sheet to move freely from the upper side of the supporting member to the lower side thereof, the used sheet can be moved to the lower side of the supporting member while the closure is in a position parallel with the receptacle. When the closure is fully opened but is parallel with the receptacle the forward portion of the supporting member can move outwardly between the supporting rods 15 a substantial distance with relation to the receptacle. This distance is sufficient to permit the used sheets to be moved about the forward end of the supporting member, although when so moved the sheets may engage the end portion of

the receptacle and will have to be pushed downwardly into the receptacle.

The sliding movement of the closure may be limited in any suitable manner to prevent the unintentional removal of the closure from the supporting rods. In the present arrangement the rear ends of the rods 15 are connected by a cross member 15a which lies close to the under surface of the closure and the closure is provided with a downwardly extending projection or projections 15b spaced from the forward end of the closure such a distance that they will engage the cross rod 15a and interrupt the movement of the closure at the desired point. The projections are here shown as formed by indentations in the upper surface of the closure.

In Figs. 5 to 7 there is shown a form of the sheet holder in which the sheet supporting member is normally supported in the receptacle but may be connected with the closure so as to move outwardly therewith when the latter is moved about its pivotal axis. As there shown the lower member is in the nature of a receptacle 29 and is of a construction similar to that above described and the closure 30 is slidably supported on rods 31 which are pivotally connected with the forward end of the receptacle in the manner described. The sheet supporting member 32 is provided at its forward end with an upwardly extending part 33 having at its upper edge a rearwardly extending lip 34. At its rear end the supporting member is provided with a hook shaped portion including a part 35 extending upwardly at substantially right angles to the longitudinal portion of the supporting member, and a downwardly extending part 36 which hooks over the upper edge of the rear end wall of the receptacle and projects rearwardly a short distance beyond the same. A sheet gripping member 37 is connected with the sheet supporting member between the ends thereof and the forward portion of the gripping member is biased upwardly toward the lip 34 to grip the forward end of the pile of sheets 38 between the same and the lip. When the closure is in its normal closed position the forward edge thereof extends beneath the lip 34 and thus supports that end of the sheet supporting member. However, the engagement of the hook shaped portion 35-36 of the supporting member with the rear end wall of the receptacle is such as to support the forward portion of the supporting member out of engagement with the bottom of the receptacle when the closure is in its retracted position. The rear end portion of the closure is provided with a downwardly extending part 39 having at its lower end a lip 40 so arranged that it will be below and spaced from the lower edge of the part 36 of the hook on the supporting member when the closure is in its normal closed position. Thus when the closure is retracted to permit the uppermost sheet 38a to be withdrawn the lip 40 will move past the part 36 of the hook, and when the closure is moved to its foremost position beneath the withdrawn sheet the lip 40 will again be below the part 36 and the forward end of the closure will be in supporting relation to the lip 34 at the forward end of the supporting member. With the parts in these positions the outward movement of the closure about its pivotal axis will cause the lip 40 to engage the hook part 36 and connect the sheet supporting member with the closure and thus cause the sheet supporting member to move with the closure outwardly from the receptacle, thereby providing free access to the

receptacle below the rear portion of the supporting member. The retained part, or copy, of the withdrawn sheet being frictionally held between the lip 34 of the supporting member and the forward end of the closure may be withdrawn, either before or after the closure is moved outwardly, and inserted in the lower compartment of the receptacle.

The sheet holder shown in Fig. 8 also comprises a receptacle 41 and a closure 42 slidably supported on rods pivotally connected with the rearwardly extending upper portion of the front end wall 44 of the receptacle. The rear end portion of this rearwardly extending part of the end wall is turned downwardly and forwardly to form a bearing or bearings 45 in which the transverse end portions of the rods 43 are supported. These bearings are adapted to engage the upper surface of the end portions of the pile of sheets and thus constitute gripping members which cooperate with an upwardly biased lower gripping member 46. The gripping member 46 is in the nature of a plate 47 the rear portion of which is pivotally connected with a second member or plate 48 rigidly secured to the rearwardly extending upper portion of the end wall 44 and extends downwardly therefrom. The adjacent edge portions of the members 47 and 48 are provided with bearings 49 to receive a hinge pin 49a about the axis of which the lower gripping member 48 moves. A spring 49b supported on the hinge pin acts on the lower gripping member and moves the same upwardly about said axis. A sheet supporting member 50, which is pivotally connected at its forward end with the gripping member 46, supports a pile of sheets 52 with the rear ends between the two gripping members. In the present instance the forward end of the supporting member extends above the gripping member 46 and is pressed upwardly by that member to grip the sheets between the same and the upper gripping member or bearing 46. Preferably the supporting member is provided at its rear end with a tab 51 to facilitate its withdrawal from the receptacle.

The sheet holder of Fig. 9 is substantially similar in its operation to the sheet holder of Fig. 8 but the sheet gripping mechanism is slightly different from that of Fig. 8. It comprises a receptacle 53 having an upwardly extending forwardly curved front end wall 54 the rearwardly extending upper portion of which is provided with a bearing or bearings 57 to receive the transverse end portion of the rods 55 on which the closure 56 is slidably mounted. The bearing or bearings 57 also have gripping engagement with the upper surface of the end portion of a pile of sheets which are supported by an upwardly biased lower gripping member 58. The lower gripping member is shown as comprising a flat plate slidably mounted on upright posts 59 rigidly supported at their lower ends in the lower portion of the receptacle, one only of the rods being here shown. Followers 60 slidably supported on the respective rods engage the lower surface gripping member 59 and are urged upwardly by springs 61 coiled about the posts 59, thus causing the sheets to be gripped between the gripping member 58 and the bearing or upper gripping member 57. A sheet supporting member 62 is pivotally connected at its forward end with the rear edge of the lower gripping member 58, as by a flexible member 62a. In this instance the forward end of the sheet supporting member terminates at the forward edge of the

lower gripping member and the latter has direct engagement with the lower surface of the pile of sheets. The sheets of the pile of sheets are preferably perforated to receive the posts 59 and to slide thereon. However, the upper ends of the posts terminate slightly below the bearing or upper gripping member 57 so that the upper sheet, which is in engagement with the upper gripping member, is above the upper ends of the posts 58 and is retained in position by friction only and can, therefore, be withdrawn from the gripping members without tearing.

In Fig. 10 there is shown a different type of sheet holder which comprises a lower member or flat plate 63 and an upper member or closure 64 slidably mounted on rods 65. The rods 65 are pivotally mounted in a bearing or bearings 66 at the rear edge of a rearwardly extending gripping member 67 which is pivotally connected with and carried by a lower member 68 which is rigidly secured to and extends rearwardly beyond the lower plate 63. An arcuate spring 69 engages the members 67 and 68 and presses the member 67 downwardly toward the rear portion of the member 68 on which the forward end of a pile of sheets 70 rests, thus causing the sheets to be gripped between the bearing or bearings 66 and the lower member 68. The lower member 68 has its upper surface in a horizontal plane of the upper surface of the plate 63 and obviously the lower member 68 may be of such length that the sheets are gripped directly to the bottom member 63 instead of the member 68.

While I have shown and described certain embodiments of my invention I wish it to be understood that I do not desire to be limited to the details thereof as various modifications may occur to a person skilled in the art.

Having now fully described my invention what I claim as new and desire to secure by Letters Patent is:

1. A sheet holder comprising a bottom member and a top member arranged to receive between them a pile of individually removable sheets, means for retaining said sheets between said members, and means for supporting said top member on said bottom member for movement about a transverse axis adjacent the forward end of said bottom member and for fore and aft movement with relation to said axis.

2. A sheet holder comprising a bottom member, elongate members connected with said bottom member for movement about a transverse axis adjacent one end of said bottom member and extending from said axis toward the other end of said bottom member, a top member supported by said elongate members for movement therewith about said axis and for movement toward and from said axis, and means for retaining a pile of individually removable sheets between said top and bottom members.

3. A sheet holder comprising a bottom member, elongate members connected with said bottom member for movement about a transverse axis adjacent the forward end of said bottom member and extending rearwardly from said axis, a top member having adjacent its respective lateral edges longitudinal guideways to receive the respective elongate members and slidably support said top member thereon, and means for retaining a pile of individually removable sheets between said top and bottom members.

4. A sheet holder comprising a bottom member, elongate members connected with said bottom member for movement about a transverse axis

adjacent the forward end of said bottom member and extending rearwardly from said axis, a top member supported by said elongate members for movement therewith about said axis and for movement toward and from said axis, a transverse member connected with and extending between the rear portions of said elongate members, said top member having a part extending downwardly therefrom to engage said transverse member and limit the rearward movement of said top member, and means for retaining a pile of individually removable sheets between said top and bottom members.

5. A sheet holder comprising a receptacle adapted to receive a pile of sheets, a closure for said receptacle, means for connecting said closure with said receptacle for movement about a transverse axis adjacent one end of said receptacle and for movement toward and from said axis, and a sheet supporting member movably supported in said receptacle, at least one end portion of said member being movable outwardly beyond said receptacle when said closure is moved about its said axis.

25 6. A sheet holder comprising a receptacle adapted to receive a pile of sheets, a closure for said receptacle, means for connecting said closure with said receptacle for movement about a transverse axis adjacent one end of said receptacle and for movement toward and from said axis, and a sheet supporting member extending for the major portion of the length of said receptacle and pivotally supported adjacent one end thereof in said receptacle, the free end portion of said member 30 being movable outwardly beyond said receptacle 35 when said closure is moved outwardly about its axis.

7. A sheet holder comprising a receptacle adapted to receive a pile of sheets, a closure for 40 said receptacle, means for connecting said closure with said receptacle for movement about a transverse axis adjacent one end of said receptacle and for movement toward and from said axis, and a sheet supporting member supported in said receptacle with its forward end portion adjacent 45 the pivotal axis of said closure and free for outward movement with relation thereto, whereby the movement of said closure from its said axis will release said forward portion of said member for movement outwardly beyond said receptacle.

50 8. A sheet holder comprising a receptacle adapted to receive a pile of sheets, a closure for said receptacle, means for connecting said closure with said receptacle for movement about a transverse axis adjacent one end of said receptacle and for movement toward and from said axis, and a sheet supporting member extending lengthwise of said receptacle, pivotally connected at its rear end with said receptacle and having its forward end adjacent the pivotal axis of said closure, whereby the movement of said closure from said axis will release the forward portion of said member for movement outwardly beyond said receptacle.

65 9. A sheet holder comprising a receptacle adapted to receive a pile of sheets, a closure for said receptacle, means for connecting said closure with said receptacle for movement about a transverse axis adjacent one end of said receptacle and for movement toward and from said axis, and a sheet supporting member supported in said receptacle with its forward end portion adjacent the pivotal axis of said closure and free for outward movement with relation thereto, the rear end portion of said member being

movable toward the open side of said receptacle as a pile of sheets on said member decreases in thickness, thereby providing increased space between said member and the bottom of said receptacle.

10. A sheet holder comprising a receptacle having bottom, side and end walls, a movable closure for said receptacle, a member within said receptacle dividing the same into upper and lower compartments and adapted to support a pile of sheets in said upper compartment, one end portion of said member being biased to a position above and spaced from said receptacle when said closure is in its open position, annular sheet attaching devices connected with and extending beyond said end portions of said member and adapted to extend through openings in said pile of sheets and to support the latter on said member, the sheets of said pile being individually movable on said annular devices from positions above said member to positions below the same and extending lengthwise thereof when said end portion of said member is spaced from said receptacle.

11. A sheet holder comprising a receptacle adapted to receive a pile of sheets, a closure for said receptacle, means for connecting said closure with said receptacle for movement about a transverse axis adjacent one end of said receptacle and for movement toward and from said axis, a sheet supporting member removably supported in said receptacle and dividing the latter into upper and lower compartments, means for retaining said pile of sheets on said member in a position from which the uppermost sheet may be withdrawn when said closure has been moved from said axis to an open position, said closure being movable to a closed position beneath the withdrawn sheet, and means operative when said closure is in said closed position to connect said supporting member with said closure for movement therewith about said axis.

12. A sheet holder comprising a receptacle adapted to receive a pile of sheets, a closure for said receptacle, means for connecting said closure with said receptacle for movement about a transverse axis adjacent one end of said receptacle and for movement toward and from said axis, and a sheet supporting member supported normally on said receptacle, said closure having means operative when said closure is in its closed position to connect said supporting member with said closure for movement therewith about said axis.

13. A sheet holder comprising a receptacle adapted to receive a pile of sheets, a closure for said receptacle, means for connecting said closure with said receptacle for movement about a transverse axis adjacent one end of said receptacle and for movement toward and from said axis, a sheet supporting member supported normally in said receptacle, said closure being movable with relation to said receptacle to an open position, and means controlled by the movement of said closure to its closed position to connect said receptacle with said closure for movement therewith about said axis.

14. A sheet holder comprising a receptacle having a bottom wall, side walls and front and rear end walls, a closure for said receptacle, means for connecting said closure with said front wall for movement with relation thereto about a transverse axis and for movement toward and from said axis, a sheet supporting member supported normally in said receptacle

and having at its front end a part with which said closure has supporting connection when in its closed position, said supporting member also having a part extending beyond said rear end wall, and said closure having at its rear end a part which extends beneath the last mentioned part of said supporting member when said closure is in its closed position and adapted to engage the same when said closure is moved about 10 said transverse axis and cause said supporting member to move with said closure.

15. A sheet holder comprising a receptacle having a bottom wall, side walls and front and rear end walls, a closure for said receptacle, means for connecting said closure with said front wall for movement with relation thereto about a transverse axis and for movement toward and from said axis, a sheet supporting member in said receptacle having at its rear end a hook shaped part which normally has supporting engagement with the rear end wall of said receptacle, said supporting member having at its front end an upwardly extending part provided at its upper edge with a lip extending rearwardly above the front end portion of said closure when the latter is in its closed position, said closure having at its rear end a part which extends beneath the outer end of said hook shaped part when said closure in its closed position and is adapted to engage said hook shaped part and impart upward movement to said receptacle when said closure is moved about said axis.

16. A sheet holder comprising a receptacle having a bottom wall, side walls and front and rear end walls, a closure for said receptacle, means for connecting said closure with said front wall for movement with relation thereto about a transverse axis and for movement toward and from said axis, a sheet supporting member in said receptacle having at its rear end a hook shaped part which normally has supporting engagement with the rear end wall of said receptacle, said supporting member having at its front end an upwardly extending part provided at its upper edge with a lip extending rearwardly above the front end portion of said closure when the latter is in its closed position, said closure having at its rear end a part which extends beneath the outer end of said hook shaped part when said closure is in its closed position and is adapted to engage said hook shaped part and impart upward movement to said receptacle when said closure is moved about said axis, and a retaining member carried by said supporting member and having an upwardly biased end projection beneath said lip to grip between the same and said lip the end portion of a pile of sheets on said supporting member.

17. A sheet holder comprising a receptacle adapted to receive a pile of sheets, a closure for said receptacle, means for connecting said closure with said receptacle for movement about a transverse axis adjacent the front end of said receptacle and for movement toward and from said axis, and a sheet supporting member supported in said receptacle for movement about an axis adjacent the front end of said receptacle, the rear portion of said supporting member being movable outwardly beyond said receptacle when said closure has been moved outwardly about its said axis.

18. A sheet holder comprising a receptacle adapted to receive a pile of sheets, a closure for said receptacle, means for connecting said clo-

11

sure with said receptacle for movement about a transverse axis adjacent the front end of said receptacle and for movement toward and from said axis, upper and lower sheet gripping members in the forward portion of said receptacle, and a sheet supporting member pivotally connected with said lower gripping member, extending rearwardly therefrom and adapted to support a pile of sheets gripped between said gripping members, the rear portion of said supporting member being free to move outwardly when said closure has been moved outwardly about its said axis.

19. A sheet holder comprising a receptacle adapted to receive a pile of sheets and having a front end wall provided with a rearwardly extending upper portion adapted to have gripping engagement with the upper surface of the end portion of a pile of sheets, a sheet gripping member supported in said receptacle below the

10

15

20

12

sheet engaging portion of said end wall and biased toward the latter, and a member pivotally connected with said gripping member, extending rearwardly therefrom and adapted to support a pile of sheets with the forward end of said pile gripped between said gripping member and the sheet engaging portion of said end wall.

BRUCE K. SLONNEGER.
